CARL M. F. FRIDEN, OF OAKLAND, CALIFORNIA.

CALCULATING MACHINE.

Application filed October 25, 1926. Serial No. 143,858.

The invention relates to calculating machines and particularly to calculating machines adapted to perform the operations of addition, subtraction, multiplication, and 5 division.

An object of the invention is to provide a calculating machine in which the multiplication or division of a number by another number is accomplished by the depression of 10 a key.

Another object of the invention is to provide a calculating machine which is automatic in its operation, to compute problems involving multiplication and division.

15 A further object of the invention is to provide a power driven calculating machine, in which the operation of the machine is initiated, in problems of addition, subtraction, multiplication and division, by the depression of a digit key representing one of 20 the factors of the calculation.

25 A further object of the invention is to provide a calculating machine which may be operated to add or subtract a given number a plurality of times without changing the setting of the machine.

30 A further object of the invention is to provide a power driven calculating machine provided with means for disconnecting the source of power from the machine, when the machine has completed the calculating operation represented by the numerical value of the depressed keys.

35 A further object of the invention is to provide a calculating machine having a reversible actuator, with two series of value keys, depression of a key of one series serving to cause operation of the actuator in a positive direction for a duration represented by the value of the depressed key, and 40 depression of a key in the other series serving to cause operation of the actuator in a negative direction for a duration represented by the value of the depressed key.

45 The invention possesses many other advantageous features, some of which with the foregoing, will be set forth at length in the following description, where I shall outline in full, that form of the invention which I 50 have selected for illustration in the drawings accompanying and forming part of the present specification. In said drawings I have shown one embodiment of my invention, but it is to be understood that I do not limit my-

self to such form, since the invention, as set forth in the claims, may be embodied in a plurality of forms.

It is manifest that the invention comprising the means for automatically stopping the operation of the calculating machine, after the calculation has been completed, may be combined with any suitable form of calculating mechanism. In the accompanying drawings, I have shown the invention embodied in a calculating machine comprising a counting mechanism actuating device consisting of a rotatable drum in which the values to be calculated are introduced, but it is to be understood that the invention is not limited to use in connection with a calculating machine having a counting mechanism actuating device of this character or to a machine having a rotatable drum for performing the calculating operation. Further, in the machine shown in the drawings, the values are entered into the counting mechanism actuating device by means of a plurality of depressible keys, but it is to be understood that other suitable or well known means may be employed for introducing the values into the device. It is preferable, however, to embody the invention in a keyboard calculating machine wherein the values are introduced into the machine by the depression of keys. The calculating machine shown in the accompanying drawings is of the true rotary type, embodying a rotatable counting mechanism actuator of the reversible cycle type, which is rotated from initial or neutral stop position through a complete cycle in either direction to perform a calculating operation.

The actuator is rotated from neutral stop position through one or more complete cycles of 360° in either direction and is stopped at neutral stop position. The counting mechanism is arranged on a carriage, normally stationary with respect to the actuator, and displaceable longitudinally to make direct action of the actuator on the various numeral wheels or figure discs of the counting mechanism possible. The actuator is rotated by an electric motor, preferably continuously energized during the use of the machine, a clutch and stop mechanism being interposed between the motor and the actuator to permit intermittent rotation of the actuator while the motor operates continu-

ously. A reversing gear is interposed between the actuator and the clutch to permit rotation of the actuator in either direction.

The machine disclosed in the present application embodies all of the features disclosed in my co-pending application, Serial Number 693,546 filed February 18, 1924, to which reference is hereby made for a more complete disclosure of the entire calculating machine. The present application relates to improvements of, and additions to the features disclosed in such co-pending application, and the claims in this application will be drawn to the features which distinguish the present machine from that shown in the co-pending application. Novel subject matter, common to both machines, will be claimed in the said co-pending application.

Referring to said drawings Figure 1 is a longitudinal vertical section through a calculating machine embodying my invention disclosing the means operated by the depression of a key for controlling the direction and duration of operation of the counting mechanism actuator.

Figure 2 is a section taken on the line 2-2 Figure 1. Figure 3 is a longitudinal vertical section of the machine showing the automatic operation keys in association with the means for determining the duration of operation of the actuator.

Figure 4 is a perspective view of the latch for holding and releasing the depressed keys.

Figure 5 is a transverse vertical section through the two rows of automatic keys, one of the keys being in the depressed position, showing the means for holding and releasing the depressed keys.

Figure 6 is a side elevation of the key having the numerical value of 1.

Figure 7 is a side elevation of the clearance key for manually releasing the depressed key.

Figure 8 is a plan or top view of a portion of the machine, a portion of the mechanism being removed to disclose the clutch and reversing gear and the means for controlling the same.

Figure 9 is a longitudinal section of a portion of the machine showing the positioning levers which connect the two series of value keys with the device for predetermining the number of operations of the actuator.

Figure 10 is a longitudinal vertical section of the machine showing the means for releasing the keys of the keyboard.

Figure 11 is an elevation of the key for positioning the parts which control the release of the keyboard keys.

Figure 12 is a longitudinal vertical section of the machine showing the clutch which controls the connection between the motor

and the actuator and the means for operating and controlling the clutch.

Figure 13 is a side elevation of the mechanism for predetermining the number of operations of the actuator.

Figure 14 is a top or plan view of the key board which is operated to control the automatic operation of the machine.

Figure 15 is a plan view of a modified form of the key board for the automatic unit.

Figure 16 is a longitudinal vertical section of the machine showing the automatic unit modified for operation in connection with the key board unit shown in Figure 15.

The machine shown in the accompanying drawing is of the key board type, in which the values are introduced into the machine by the depression of keys. The depression of a key, introduces a value corresponding to the numeral on the key, into a rotatable drum within the machine, rotation of the drum in either direction being effected to accomplish the calculating operation. The values introduced into the drum are transmitted, on rotation of the drum, to the numeral wheels of a counting mechanism, which, for the purpose of making direct action of the selected values on the numeral wheels of highest value possible, is disposed in parallel displaceable relation to the value selecting mechanism axis.

The machine shown in the drawings is similar in appearance and in general construction to the machine shown in my above mentioned co-pending application, Serial Number 693,546. The machine comprises a reversible rotary actuator for the numeral wheels and the values to be calculated are entered into the actuator by the depression of keys, not shown. The means for introducing the values into the actuator by the depression of keys is fully disclosed in my co-pending application, and since no change has been made in that feature of the machine, it is believed unnecessary to repeat the disclosure herein.

The numeral wheels 3 are arranged in the longitudinally displaceable carriage 4 and are acted upon, through the intermediate gear 5 by the reversible rotary actuator 6 which includes a plurality of selective actuating elements 7. The actuator is driven by the motor 8 and suitable instrumentalities are interposed between the motor and the actuator to control the rotation, the direction of rotation and the duration of rotation of the actuator. Interposed between the motor and the actuator is a clutch member 9 which serves to control the rotation of the actuator. The clutch member comprises a driving shaft 12 and a housing or driven element 13, the latter being connected to the actuator and the former being connected to the motor through suitable gearing as shown

in Figure 8. The gear train between the motor and the driving shaft 12 includes the pinion 14 and the gears 15, 16, and 17. The gears 15 and 16 are held in frictional engagement by the spring 18, and these gears 15 and 16 are mounted on a hollow shaft through which the reversing gear shifting rod 19 extends. The reversing gear 21 which is provided with a grooved shifting 10 collar 22 is splined to a stub shaft extending from the driven housing 13. Engaging the grooved collar 22 is a shifting yoke 23 which is secured to the shifting rod 19. The reversing gear 21 is shiftable longitudinally 15 into mesh with either the gear 24 or the gear 25. The gears 24 and 25 are in mesh and the gear 25 meshes with the gear 26 which in turn meshes with the gear 27 of the actuator shaft. By shifting the gear 21, the direction of rotation of the actuator with respect to the clutch is reversed. The shifting rod 19 is moved longitudinally by the shifting cam 28, the edge of which engages in a groove in the rod 19. The cam 28 is pivoted 20 to the frame of the machine at 31 and is rocked about its pivot to effect the shifting 25 of the reversing gear.

The clutch comprises the driving shaft 12 and the driven housing 13. Secured to 30 the driving shaft 12 is a ratchet wheel 32 which is adapted to be engaged by the pawl 33 pivoted to the housing 13. The pawl is normally pressed toward engagement with the ratchet wheel by the spring 34 and is 35 held from engagement with the ratchet wheel by the clutch control lever 35 which extends through an aperture in the housing into engagement with the clutch 36 of the pawl 33, rocking the pawl on its pivot and 40 holding it out of engagement with the ratchet 32. When the end of the clutch control lever is disposed in the aperture in the housing, the housing is locked in normal or full cycle position. Operation of 45 the clutch lever 35 therefore serves to unlock the housing and permit engagement of the clutch member. The clutch control lever 35 is normally held in position to lock the clutch in full cycle position by the 50 spring 37.

The machine also embodies means for predetermining the number of operations of the actuator either in a forward or reverse direction. This means comprises two series 55 of value keys connected to a controlling mechanism which is operated in time with the actuation of the machine and which serves to cause disengagement of the clutch and locking of the clutch housing in full cycle position when the machine has operated a number of times represented by the value of the depressed key. In Figure 14 I have shown the automatic key board unit comprising the services of value keys 41 depression of which cause rotation of the ac-

tuator in one direction and the series of value keys 42 depression of which cause rotation of the actuator in the reverse direction. Each series comprises nine consecutively numbered keys and a clearance key 70 43 associated with each row of keys for releasing the depressed keys therein. In the present arrangement, depression of any of the keys 41 causes forward rotation of the actuator as in performing problems in 75 addition, and depression of any of the keys 42 causing reverse rotation of the actuator as in performing problems in subtraction. Depression of a key 41 serves to unlock and engage the clutch and position the automatic control unit in the position represented by the value of the depressed key. Depression of any one of the keys 42 serves to perform these functions and in addition shifts the reversing gear from its normal 80 forward drive position to reverse drive position. The reversing gear shifting cam 28 is normally held in forward drive position by the spring 45 connected to the rock lever 46 which is connected to the shifting cam 90 28 by the link 47. In Figure 1, the cam 28 is shown in the reverse drive position, having been moved to such position by depression of the key 42 in the reverse drive row of keys. Each reverse drive key 42 is provided on its shank 51 with a cam projection 52 which fits into a notch 53 in the slide bar 54 so that as a key 42 is depressed, the slide bar is moved forward. At its forward end, the slide bar 54, is provided with 100 a pin 55 which fits in a slot in the lever 56, which is pivoted intermediate its end on the bracket 57. Pivoted to the lower end of the lever 56 is a rod 58 having a reduced end 59 which extends through an 105 aperture in the link 47, the link being bent at the aperture, so that backward movement of the rod 58 causes backward movement of the link. Therefore, when any of the keys 42 is depressed, the link 47 is moved to 110 position the cam 28 in reverse drive position. The row of keys 41 is not provided with such reverse drive means. So that when a key 41 is depressed, the cam 48 remains in forward drive position, being held 115 in such position by the spring 45. When the operation represented by the value of the depressed key is completed, and the key released, the spring 45 returns the slide 54 to normal position.

Each of the rows of keys 42 and 41 is provided with means whereby the depression of a key serves to unlock the clutch housing and cause engagement of the clutch. As stated hereinbefore, the clutch is normally locked in full cycle position by the clutch lever 35 which is held in engagement with the clutch housing by the spring 37. The clutch control lever 35 is provided on its end remote from the clutch housing engaging 120

- end with a pin 61 which normally lies in an upwardly extending notch 62 in the end of the clutch control bar 63, which bar is normally held in retracted position by the spring 64. Extending transversely from the bar 63 is a pin 65 which lies directly behind the key operated finger 66. The finger 66 is secured to a gate 67, common to both rows of keys 41 and 42, and which is moved 5 backward by the depression of any key. Backward movement of the gate and consequently the finger 66, causes backward movement of the clutch bar 63 against the action of the spring 64, causing the clutch control lever 35 to rock on its pivot and move the end thereof out of engagement with the clutch housing 13. Therefore, depression of any of the keys 41 or 42, will cause the unlocking of the clutch housing and the engagement of the clutch. Each of the keys 41 and 42 is provided on its shank 51 with a cam projection 69 which extends through a slot in the slide bar 71. There is a slide bar associated with each row of keys and 10 both slide bars at their rear ends are in contact with the gate 67. Therefore, as either of the keys is depressed the slide bar 71 is moved backward to rock the gate 67 to cause engagement of the clutch.
- 15 30 Means are provided for disengaging the clutch and locking the clutch housing when the actuator has operated a number of times corresponding to the value of the depressed key. Associated with each row of keys 41 and 42 (Fig. 3) is a value selecting lever which in the present instance comprises a duplex lever. The duplex lever comprises a lever arm 73 pivoted at its forward end to the fixed bracket 74 (Fig. 9), and a lever arm 75 pivoted at its rear to the fixed bracket 76, the two lever arms being pivoted together intermediate their ends by the pivot 77. The forward end of the lever arm 75 is in alignment with the rear portion of the lever arm 73 and these aligned portions of the lever arms underlie the shanks of the keys so that depression of a key causes selective movement of the rear end of the lever arm 73. The two lever arms 73 of the two 20 rows of keys 41 and 42 are connected together at their rear ends where they are connected to the automatic selecting unit. Therefore, depression of a key in either row 41 or 42, serves to position the selecting unit in the position corresponding to the value of the depressed key. The automatic selecting unit which is shown in Figures 3 and 13 is fully described in my application hereinbefore referred to. Disposed within 25 the machine is a slidable plate 81 having a stepped edge 82, the plate being normally held in a forward position by the spring 83. Backward movement of the slide plate 81 serves to free the clutch control lever 35 from the clutch bar 63, thus causing the
- lever to engage and lock the clutch housing. The slide plate 81 is moved backwards during the last operation of the actuator, as determined by the value of the depressed key. Associated with the stepped plate 81 is a rack bar 84 which is in mesh with a pinion 85. The pinion is engaged by a tooth 85^a carried by the clutch housing, so that on each rotation of the clutch housing, the rack bar is moved backward one step. A spring 78 pressed pawl 87, holds the rack bar in the retracted position. Pivoted to the front end of the rack bar 84 is a lever 90 carrying a pin 86 which lies in the plane of the stepped edge 82 of the slide plate 81. The lever 90 80 is angularly adjustable about its pivot on the rack bar 84, to bring the pin into alignment with a selected step on the front face of the plate 81, the successive steps differing from each other in the value of one, so that, with the lever 90 set in a selected position, the pin 86 comes into contact with the stepped face when the actuator has rotated a number of times which is one less than the value selected by the depression of the key. On 85 the subsequent rotation of the actuator, the pin moves the slide plate 81 backward, and this backward movement of the slide plate operates to release the clutch control lever 35. Pivoted to the slide plate 81 is a cam lever 88 the rear face of which is in engagement with a fixed abutment 89, so that backward movement of the lower end of the cam lever, causes the lever to rock about the abutment. Extending laterally from the clutch control bar 63 is a pin 91 which lies in contact with the cam face 92 of the lever 88, so that rotation of the lever 88 about its pivot moves the pin 91 upward, which motion serves to lift the clutch control bar 63 100 out of engagement with the pin 61 on the clutch control lever, permitting the spring 37 to move the clutch control lever 35 to bring the rear ends thereof into contact with the surface of the clutch housing 13, so that the projection on the ends of the clutch control lever 35 drops into the aperture in the clutch housing locking the housing in full cycle position and moving the dog 33 to cause disengagement of the clutch. The 105 lever 88 is provided on its upper end with a lip 93 which overlies the detent 87 so that rocking movement of the lever 88 serves to raise the detent and release the rack bar 84 which is then returned to its normal position 110 by the spring 94.
- 115 The actuating lever 90 is selectively positioned by depression of the keys in either row 41 or 42. The lever arms 73 associated with the two rows of keys engage, at their rear ends, a pin 95 projecting from the lever 96 which is pivoted intermediate its end to the frame 97 of the automatic rotation controlling mechanism and which is provided at its other end with a pin 98 which extends in- 115

to a slot 99 in the adjustable lever 90. Therefore, depression of a key in either of the rows 41 or 42 serves to position the lever 90 and consequently the pin 86, so that the 5 slide plate 81 will be moved backward when the actuator has operated a number of times represented by the value of the depressed key.

Means are provided (Fig. 5) for retaining the selected depressed key 41 or 42 in depressed position and for releasing the key when the operation represented by the value of the key has been completed. Each key stem 51 is provided on its side with two 10 notches 101 and 102 and each row of keys is provided with a detent bar, the row 41 being provided with a detent bar 103 and the row 42 being provided with a detent bar 104. The detent bars 103 and 104 are pivoted at 15 their ends to the frame of the key unit and are connected together by the screw link 105, so that both bars are simultaneously rocked to release the depressed key. The bar 104 is provided with an extending tongue 106 to 20 which is connected a spring 107 which tends to hold the bar in key stem engaging position. Means are provided for rocking the bars 103 and 104, on the backward movement of the slide plate 81, so that the depressed 25 keys will be released. Pivoted within the machine is a bell crank lever 108, the forward end of which overlies the tongue 106, the other end being connected by the link 109 with the slide plate 81. As the slide 30 plate 81 is moved backward by the pin 86, the forward end of the lever 108 presses downward on the tongue 106, rocking the detent bars 103 and 104 and releasing the depressed key. 35 The keys 41 and 42 representing values from 2 to 9 inclusive are of the same construction. The keys 41' and 42' having the value of 1 are not provided on their sides with notches which are adapted to be engaged by the detent bars for holding these 40 keys depressed. The depression of either of the number 1 keys positions the slide 90 in the number 1 position and at the same time initiates the operation of the machine, so 45 that the pin 86 is immediately brought into contact with the stepped face of the slide, and this occurs before the key can return to raised position, and consequently there is no need of providing means for holding these 50 keys depressed. Each clearance key 43 is provided on its side with a cam surface 43', which is engaged by the detent bar, so that as the key 43 is depressed, the bar is rocked to release any depressed key. 55 The lever 90 is normally positioned with the pin 86 in the zero position, and, when the machine is operated other than by the depression of one of the keys 41-42, the lever 90 remains in the zero position. The 60 rack bar 84 is moved backward one step

for each rotation of the actuator, and, when the pin 86 is in the zero position, means are actuated, for releasing the rack bar so that it swings forward to its normal position. Pivoted to the frame 97 is a lever 112 having 70 a cam shaped front end 113 with which the pin 86 is in contact when the pin is in normal position. The other end of the lever 112 underlies the pin 114 projecting from the end of the latch lever 87 so that as the pin 86 is moved backward by backward movement of the rack 84, the lever 112 is rocked on its pivot, raising the latch 114 and releasing the rack bar 84, which is immediately returned to normal position by the spring 94. Therefore, when the machine is not operated by depression of one of the keys 41 or 42, the rack bar is merely oscillated back and forth through one step. During this movement the slide plate 81 is not moved and consequently the clutch control lever 35 is not released. 75 80 85

The machine is also provided with starting control keys 121 and 122 depression of which respectively causes rotation of the actuator in a reverse or forward direction. These keys (Fig. 12) cooperate with a rocking plate 123 which is connected to the clutch control bar 63, depression of either of the keys serving to rock the plate 123 backward to remove the clutch control lever 35 from engagement with the clutch housing. The keys 121 and 122 also cooperate with the rocking lever 46 to which the link 47 is connected. The lever 46 is normally held in the forward position by the spring 45. Depression of the starting control key 122 will normally have no effect on the rocking lever 46 whereas depression of the negative starting control key 121 will rock the lever 46 to 105 shift the cam 28 to reverse the driving gear. Therefore, depression of the key 121 will cause the actuator to be rotated in a reverse direction, and depression of the key 122 will cause the actuator to be rotated in a forward 110 direction. 115

Means are provided whereby the rotation of the actuator caused by the depression of either key 121 or 122 will be limited to one rotation or may continue as long as the key is held depressed. For this purpose, the machine is provided with a key 124 (Figs. 10 and 11) which I have designated as the plus and minus key. When this key is in its elevated position, the actuator will rotate as long as the starting control key is held depressed. When it is desired to perform problems in addition or subtraction, the key 124 is depressed and, by virtue of the projection 125 thereon cooperating with the slide 126, the key is held in its depressed position. A clear key 127 is provided for shifting the slide 126 and releasing the depressed plus and minus key 124. Secured to the key 124 is an arm 128 which 120 125 130

overlies the key set lever 75 (Fig. 9) and, when the key 124 is depressed, the lever 75 is moved to the 1 position, that is moved to a position to set the pin 86 in the 1 position. With the pin 86 in this position, the first rotation of the clutch will cause the rack bar 84 to move the slide plate 81 to cause the release of the clutch. Therefore, when the key 124 is depressed, depression of either key 121 or 122 will result in only one rotation of the actuator, regardless of whether or not the key 121 or 122 is held depressed. The clearance key 127 also serves to release the depressed keys of the keyboard which have been depressed to introduce the first factor into the machine. As shown in my copending application above referred to, these keyboard keys are held in depressed position by the slides 131, one of these keys 132, being shown in Figure 10 for the purpose of illustration. The slide 131 is normally held forward by the spring 133 and backward movement of the slide results in the release of the keyboard key. The slides are provided at their rear ends with upturned ends 134 and arranged in front and common to all of the upturned ends is a pivoted gate 135. Pivoted to the frame of the machine, and having one face thereof in contact with the gate 135, is a lever 136, the front end of which underlies the stem of the clear key 127. Therefore, when the key 127 is depressed, the lever 136 is rocked on its pivot, causing the gate 135 to rock to move all of the slides 134 and thereby release the depressed keyboard keys. The gate 135 may also be rocked by the oscillating arm 138 which is provided on its forward end with a hook which is adapted to engage the gate when the arm 138 is positioned to move in a path intersecting the gate. Normally, the arm 138 moves in a path below the gate but, upon the depression of the plus and minus key 124, the key bears against the lever 139 which carries on its inner end, a projection 141 on which the lever 138 rides. When the key 124 is depressed the projection 141 is raised, moving the hook on the end of the arm 138 into a position so that in its movement it intersects the gate so that, as the arm 138 is oscillated and reciprocated, during the operation of the machine, the lever 135 is rocked and consequently the keyboard keys are released during the first operation of the machine. This occurs, when the key 124 has been depressed. When the key is in its elevated position however the hook on the end of the arm 138 passes below the gate 135 so that the keys of the keyboard are not released. The key 124 is depressed when it is desired to perform problems in addition and subtraction, but when it is desired to perform problems in multiplication and division, the key 124 is restored

to its elevated position. In Figures 15 and 16 I have shown a modified form of the machine embodying the present invention in which only a single row of rotation controlling keys 142 are employed. Normally, the depression of any of these keys will cause rotation of the actuator in a forward direction for a number of times represented by the value of the key. In this modified form, the machine is provided with a minus or reverse key 143 which may be latched in depressed position. This key is connected by means of the bell crank lever 144 with the rod 145 which is associated with the reversing link 47 in the same manner as the rod 58 in Figure 1. Depression of the key 143 therefore shifts the reversing mechanism to cause reverse drive of the actuator so that with such key 143 depressed, depression of one of the keys 142 will cause rotation of the actuator in a reverse direction for the number of times represented by the depressed value key. In other respects, the machine shown in Figures 15 and 16 is identical with the machine shown in the other drawings.

I claim:

1. In a calculating machine, numeral wheels, a reversible rotary actuator therefor, means for introducing one factor of the calculation into the actuator, keys for introducing the second factor into the machine, a motor for rotating the actuator and means operated by the depression of a key for causing the motor to rotate the actuator in the desired direction and means correlated with the actuator for causing the motor to rotate the actuator for the duration required to effect the calculation represented by the value of the depressed key.

2. In a calculating machine, numeral wheels, a reversible rotary actuator therefor, means for introducing one factor of the calculation into the actuator, keys for introducing the second factor into the machine, a motor for rotating the actuator, a reversing gear interposed between the motor and the actuator to cause rotation of the actuator in either direction and means operated by the depression of a key for engaging the reverse gear and causing the motor to rotate the actuator in the direction and for the duration required to effect the calculation represented by the value of the depressed key.

3. In a calculating machine, numeral wheels, a reversible rotary actuator therefor, means for introducing one factor of the calculation into the actuator, keys for introducing the second factor into the machine, a motor for rotating the actuator, a clutch interposed between the motor and the actuator, a reversing gear interposed between the motor and the actuator and means operated by the depression of a key for controlling the clutch and reversing gear to cause

the motor to rotate the actuator in the direction and for the duration required to effect the calculation represented by the value of the depressed key.

5 4. In a calculating machine, numeral wheels, reversible actuating means therefor and means including a plurality of keys selectively operable by a single manual stroke to initiate and effect continuous forward or reverse movement of said actuating means and means correlated with the actuator for stopping the actuator after it has operated for the number of cycles of operation determined by the value of the selected 15 key.

5. In a calculating machine, numeral wheels, reversible actuating means therefor, a motor, a reversing gear interposed between the motor and the actuating means, a row 20 of keys and means actuated by the depression of any key for causing the motor to rotate the actuating means in a reverse direction.

6. In a calculating machine, numeral 25 wheels, reversible actuating means therefor, and means to initiate and effect continuous forward or reverse movement of said actuating means through a selected number of cycles of operation including two rows of keys, and means operated by the depression of any key in one row serving to cause forward movement of the actuating means and by the depression of any key in the other row to cause reverse movement of the actuating means.

7. In a calculating machine, numeral 30 wheels, reversible actuating means therefor, and means operative by a single manual stroke to initiate and effect continuous forward or reverse movement of said actuating means through a selected number of cycles of operation including two rows of numerical value keys, means operated by the depression of a key in one row serving to cause forward movement of the actuating means for a duration corresponding to the value of the depressed key and by the depression of a key in the other row to cause reverse movement of the actuating means for a duration 35 corresponding to the value of the depressed key.

8. In a calculating machine, numeral 40 wheels, reversible actuating means therefor, a motor, reversing gearing interposed between the motor and the actuating means, means for controlling the number of rotations of the actuating means, two rows of keys for setting said controlling means and means actuated by the depression of a key in 45 one of said rows for shifting said reversing gearing.

9. In a calculating machine, numeral 45 wheels, reversible actuating means therefor, a motor for driving said actuating means, a normally disengaged clutch interposed be-

tween the motor and the actuating means, two rows of keys for controlling the direction and duration of operation of the actuating means and a single clutch engaging means operatively connected to the keys in 70 the two rows.

10. In a calculating machine; numeral wheels, reversible actuating means therefor, a motor, a normally disengaged clutch interposed between the motor and the actuating means, a reversing gearing interposed between the clutch and the actuating means, means for predetermining the number of operations of the actuating means, a row of keys of different numerical value, and means 75 operative by the depression of a key for operating the reversing gearing engaging the clutch and positioning the operation predetermining means in the position corresponding to the value of the depressed key.

11. In a calculating machine, numeral wheels, reversible actuating means therefor, a motor, reversing gearing interposed between the motor and the actuating means, means for predetermining the number of operations of the actuating means, a row of keys of different numerical value and means operative by the depression of a key for shifting the reversing gearing and positioning the operation predetermining means in 80 the position corresponding to the value of the depressed key.

12. In a calculating machine, numeral wheels, reversible actuating means therefor, a motor, means for controlling the direction 90 of operation of the actuating means, means for controlling the duration of operation of the actuating means and a plurality of value keys, depression of any key serving to position the direction controlling means and the duration controlling means in accordance with the sign and value of the depressed key.

13. In a calculating machine, numeral 95 wheels, reversible actuating means therefor, a motor for driving said actuating means, a plurality of value keys and means operated by the depression of a value key for determining the direction of operation of the actuating means.

14. In a calculating machine, numeral 100 wheels, a reversible actuating means therefor, a motor, reversing gearing interposed between the motor and the actuating means, means normally holding said reversing gearing in forward drive position, a plurality of keys for determining the duration of operation of the actuating means and means operated by the depression of any key for moving the reversing gearing to reverse drive 105 position.

15. In a calculating machine, numeral 110 wheels, reversible actuating means therefor, a motor, reversing gearing interposed between the motor and the actuating means, a

normally disengaged clutch between the motor and the actuating means, a plurality of value keys for determining the direction of operation and the duration of operation of the actuating means and means actuated by the depression of any key for causing engagement of the clutch.

16. In a calculating machine, numeral wheels, reversible actuating means therefor, a motor, a plurality of value keys of different sign, means actuated by the depression of a key for determining the direction and duration of operation of the actuating means, means for holding the depressed key depressed and means operative at the end of the calculation for releasing the depressed key.

17. In a calculating machine, numeral wheels, reversible actuating means therefor, a motor, means for connecting the motor to and disconnecting it from the actuating means and calculating keys operative to determine the duration of connection of the motor to the actuating means and the direction of operation of the actuating means.

18. In a calculating machine, numeral wheels, a reversible rotary actuator therefor, a motor normally disconnected from the actuator, keys for determining the direction and number of rotations of the actuator, means operated by the depression of a key for connecting the motor to the actuator and for determining the direction of rotation of the actuator and means for disconnecting

the actuator from the motor when it has rotated the number of times represented by the value of the depressed key.

19. In a motor driven calculating machine, numeral wheels, a reversible rotary actuator therefor, clutching and reversing mechanism between the motor and the actuator, a plurality of keys of different numerical value, means operative by the depression of a key for operating the clutching and reversing mechanism and means operative by the depression of a key for predetermining the number of rotations of the actuator.

20. In a motor driven calculating machine, numeral wheels, a reversible rotary actuator therefor, means between the motor and the actuator for connecting the motor to the actuator and for determining the direction of rotation of the actuator, a plurality of keys of different numerical value, means operative by the depression of a key for connecting the motor to the actuator and determining the direction of rotation of the actuator, means driven in time with the actuator operative to disconnect the motor from the actuator at the end of a predetermined number of rotations of the actuator and means operative by the depression of a key for adjusting the said rotation controlling means.

In testimony whereof, I have hereunto set my hand.

CARL M. F. FRIDEN.
